190,815

COMBINED CLOTHES AND SHOE RACK

Rosemary L. Stones, 1310 Robin St., Merritt Island, Fla.

Filed Oct. 7, 1960, Ser. No. 62,412

Term of patent 14 years

(Cl. D33—8)

FIG. 1.

FIG. 2.

FIGURE 1 is a perspective view of a combined clothes and shoe rack showing my new design; and

FIGURE 2 is a side elevational view thereof.

I claim:

The ornamental design for a combined clothes and shoe rack, as shown.

References Cited in the file of this patent

UNITED STATES PATENTS

D. 162,926 Berkowitz ----- Apr. 17, 1951

1,571,659	Conklin -----	Feb. 2, 1926
1,687,521	Stallworth -----	Oct. 16, 1928
2,110,158	Keeler -----	Mar. 8, 1938
2,440,507	Geralds -----	Apr. 27, 1948

OTHER REFERENCES

Continental Catalog for 1956, page 595, upper right, serving cart.

Hardware Age, Jan. 3, 1957, page 17, bottom left, planter stand.